UNITED STATES PATENT OFFICE.

SAMUEL L. SHELLENBERGER, OF DENISON, TEXAS.

SADDLE-STIRRUP.

SPECIFICATION forming part of Letters Patent No. 267,728, dated November 21, 1882.

Application filed July 3, 1882. (No model.)

To all whom it may concern:

Be it known that I, SAMUEL L. SHELLENBERGER, of Denison, in the county of Grayson and State of Texas, have invented a certain new and useful Improvement in Saddle-Stirrups, of which the following is a full, clear, and exact description, reference being had to the accompanying drawings, forming part of this specification.

10 My invention relates to those stirrups which are provided with foot-pieces adapted to oscillate thereon; and my object is to simplify the construction of the stirrup, and at the same time provide means whereby the foot-piece can 15 have limited universal movement on its supporting device.

My improved stirrup consists of a plain metal ring, a foot-piece, a staple securing the foot-piece to the ring, permitting the foot-piece 20 to rock, vibrate in a horizontal plane, or careen on the ring, and, finally, a hood having a side extension to guide the foot onto the foot-piece, as hereinafter described. As heretofore 25 constructed the foot-piece has been merely pivoted in the frame, so as to rock on its bearings.

Figure 1 is a perspective view of my improved stirrup adapted for the right foot. Fig. 2 is a longitudinal section, illustrating 30 in broken lines the positions it can assume when rocked. Fig. 3 is a side view of my stirrup, adapted for the left foot, showing in broken lines the forward and rear inclined positions that the ring can assume while the foot-piece remains horizontal. Fig. 4 is a bottom view thereof, showing in broken lines the 35 positions the foot-piece can assume when vibrated in a horizontal plane. Fig. 5 is a transverse

section on the line 5 5, Fig 4, showing in broken lines the foot-piece careened in opposite 40 directions.

A represents the foot-rest, which is preferably made of wood, formed neatly, to receive the foot, and provided with a curved groove, a, having flaring entrances a' a''. It rests within 45 and is secured to a ring, B, by a staple, E. As thus secured to the ring it will rock, vibrate in a horizontal plane, or careen freely therein and thereon, assuming any position required, according to the position and pressure of the 50 foot upon it, causing no undue strain upon any part of the foot. The front part of the support A is covered by a hood, C, which protects the foot and holds it in place upon the support. The hood C has an extension, D, on 55 the inside of the foot-piece to guide the foot into the stirrup in mounting. F is the supporting-strap for the stirrup.

Having thus described my invention, the following is what I claim as new therein and desire to secure by Letters Patent:

1. The improved stirrup, consisting of a plain ring, B, foot-piece A, staple E, and hood C, having side extension, D, the said foot-piece being adapted to rock, vibrate in horizontal 65 plane, or careen in the ring, and the said extension being adapted to guide the foot onto its supporting-piece, as set forth.

2. The combination, in a stirrup, of a foot-piece formed with transverse curved groove a, 70 having flaring entrances a' a'', ring B, and staple E, as set forth.

SAMUEL L. SHELLENBERGER.

Witnesses:

JAMES R. YOUNG,

J. B. FRIEDHEIM.
